US0D1023006S

(12) **United States Design Patent** (10) **Patent No.:** **US D1,023,006 S**
(45) **Date of Patent:** **** Apr. 16, 2024**

(54) **CASING SUPPORT MEMBER**

(71) Applicant: **CHENBRO MICOM CO., LTD.**, New Taipei (TW)

(72) Inventor: **Chiung-Wei Lin**, New Taipei (TW)

(73) Assignee: **CHENBRO MICOM CO., LTD.**, New Taipei (TW)

(**) Term: **15 Years**

(21) Appl. No.: **29/795,449**

(22) Filed: **Jun. 18, 2021**

(30) **Foreign Application Priority Data**

May 14, 2021 (TW) 110302534

(51) **LOC (14) Cl.** **14-02**

(52) **U.S. Cl.**

USPC **D14/432**

(58) **Field of Classification Search**

(57) **CLAIM**

The ornamental design for a casing support member, as shown and described.

DESCRIPTION

FIG. 1 is a front, top, left perspective view of a casing support member, showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Shading is used to illustrate the curvature of the part and not color.

1 Claim, 7 Drawing Sheets
